UNITED STATES PATENT OFFICE.

CARL MERCER, OF SPERRY, OKLAHOMA.

VALVE-COUPING.

1,163,435.

Specification of Letters Patent.

Patented Dec. 7, 1915.

Application filed October 31, 1914. Serial No. 869,606.

To all whom it may concern:

Be it known that I, CARL MERCER, a citizen of the United States, residing at Sperry, in the county of Tulsa and State of Oklahoma, have invented certain new and useful Improvements in Valve-Couplings; and I do hereby declare the following to be a full, clear, and exact description of the invention, such as will enable others skilled in 10 the art to which it appertains to make and use the same.

This invention comprehends certain new and useful improvements in valve couplings and has for its primary object to provide a 15 coupling of this character which will be especially adapted for coupling together the valve piston and the standing valve in the working barrel of oil wells.

The invention has for another object to 20 provide a valve coupling which will be constructed in such manner that it may be readily engaged with or disengaged from the standing valve.

The invention has for a further object 25 to provide a coupling of this character formed of two pieces, one of which may be rotated upon the other and secured to the standing valve or locked against rotation upon the second part for the purpose of 30 pulling the standing valve at the same time as the pulling of the valve piston.

The invention has for a further object 35 to provide a two part coupling of this character which will be of exceedingly simple construction and operation and which may be readily secured to the valve piston and the standing valve of oil well apparatus and engage with or disengage from one another, as occasion may require.

40 The invention has for a further object to generally improve and simplify the construction and operation of devices of this character and increase the efficiency thereof without materially increasing the cost of 45 the same.

With the above and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which—

Figure 1 is a longitudinal vertical section through a valve piston of an oil well apparatus, showing the two parts of my coupling connected with the valve piston and standing valve and disconnected from one another. Fig. 2 is a detail enlarged longitudinal section through the cylindrical member of my coupling. Fig. 3 is an enlarged detail perspective view of the coupling pin 65 of my coupling adapted to be secured to the standing valve, and Fig. 4 is a bottom end view of the cylindrical member of the coupling.

Referring more particularly to the drawing in which similar reference characters designate corresponding parts throughout the several views, 1 designates the working barrel of an oil well apparatus within which are positioned the standing valve 2 and the 70 valve piston 3, which latter is mounted upon the sucker rod in the usual manner. It will also be understood that the standing valve 2 and the valve piston 3 are of the usual construction and threaded in the collar 75 5 connecting the upper end of the upwardly converging arms 6 of the valve 2 is the shank of my coupling pin 7, upon the opposite sides of the upper end or head 8 of which are formed the vertical longitudinal 80 ribs 9.

Threaded upon the lower end of the valve piston 3 is my coupling sleeve 10 which has its upper end interiorly threaded, as shown at 11, and is provided with the circular 90 flange 12 immediately below the threaded portion 11, said flange 12 being provided in its lower edge at diametrically opposite points with upwardly extended cut-away 95 portions 13 to receive the upper end of the vertical or longitudinal ribs 9 on the head 8 of the coupling pin 7 when the coupling pin head is within the sleeve 10 and the latter forced downwardly after being turned to bring the cut-away portions 13 of the 100 flange 12 above the ribs 9, as will be readily understood by referring to the drawings.

The sleeve also has formed in its lower end a circular inner flange 14 which has opposite portions cut-away to form the guide slots 15 for the ribs 9 to permit the sleeve 10 to be engaged with or disengaged from the head 8 of said coupling pin 7. The lower flange 14 is also provided between the guide slots 15 with substantially V-shaped recesses 16 formed in its upper edge by cutting away portions thereof so that after the 105 110

sleeve 10 has been moved to position over the head 8 of the coupling pin 7 to bring the head 8 between the flanges 14 and 12, the sleeve 10 may be given a quarter turn and 5 then drawn upwardly to place the lower end of the ribs 9 in the recesses 16 and thereby lock the coupling pin 7 for rotation with the coupling sleeve 10.

It will be understood that the cut-away 10 portions 13 of the upper flange 12 are between the recesses 16 and in alignment with the guide slots 15, whereby when the sleeve 10 is forced downwardly over the head 8 and moved to its lowermost position, the upper 15 end of the ribs 9 will be engaged in the cut-away portions 13 of the upper flange 12 and the coupling pin 7 thereby locked for rotation with the sleeve 10. Upon upward movement of the coupling sleeve 10, however, said sleeve 10 will be drawn from over 20 the head 8, the ribs 9 of said head 8 passing out by way of the guide slots 15 in the lower flange 14.

From the foregoing it will be readily seen 25 that the coupling pin 7 and coupling sleeve 10 may be readily attached to the standing valve and valve piston respectively and the standing valve may be pulled at the same time the valve piston is pulled. A great 30 advantage of this device is that in case the sucker rod becomes unscrewed by accident, letting the coupling sleeve drop over the coupling pin, they may be screwed together again without coupling together the sleeve 35 and pin, it being impossible to turn the coupling sleeve 10 as the ribs 9 of the head 8 of the coupling pin 7 are engaged in the cut-away portions 13 of the upper flange 12 in the sleeve 10 and the coupling pin 7 is 40 stationary in the standing valve 2. Another advantage of this coupler is that in case the standing valve and valve piston are allowed to bump together when the well 45 is pumping, there is no danger of coupling together the sleeve and pin as there are no threads exposed. When it is desired to pull the clamping valve, however, all that is necessary is to permit the coupling sleeve to drop over the coupling pin, raise the coupling pin slightly and then give the sucker rods about a quarter turn, thereby coupling 50 together the coupling sleeve 10 and coupling pin 7, making it possible to pull both

valves at the same time. Still another advantage of this device is that in case you 55 couple onto a standing valve which has become fast and cannot be pulled, it is just as easy to uncouple them as it was to couple them together.

While the preferred embodiment of the 60 invention has been shown and illustrated, it will be understood that minor changes in the details of construction and arrangements of parts may be made without departing from the spirit and scope of the invention 65 as claimed or sacrificing any of the advantages thereof.

What is claimed is:—

1. A coupler of the character described including a coupling sleeve having upper 70 and lower flanges formed therein, the lower flange being provided with opposite guide portions, and a coupling pin having longitudinal ribs formed on its head for movement 75 through the guide grooves of the lower flange and engagement in the cut-away portions of the upper and lower flanges of said coupling sleeve.

2. A coupler of the class described comprising a coupler sleeve for engagement with a valve, a coupling pin for engagement with the second valve and having a head provided with longitudinal ribs, said coupling sleeve having an interior flange with 85 guide slots extended therethrough at diametrically opposite points, said lower flange having substantially V-shaped recesses in its upper edge to receive the ribs of the coupling pin and thereby lock the same with 90 the coupling sleeve, and an interior upper flange carried by said coupling sleeve and provided with said rib receiving recesses in its lower edge at right angles to the recesses in the lower flange and in alignment with 95 the guide slots of the lower flange, the upper end of said coupling sleeve being interiorly threaded while the lower end of the coupling pin is exteriorly threaded.

In testimony whereof I affix my signature 100 in presence of two witnesses.

CARL MERCER.
